UNITED STATES PATENT OFFICE.

JAMES N. HARROD, OF PALO ALTO, CALIFORNIA.

BOBBIN RACK.

Application filed October 12, 1925. Serial No. 62,092.

This invention relates to an improved rack which is especially, although not necessarily, designed for supporting and maintaining thread bobbins in an orderly fashion 5 for convenient use, the same being particularly useful in association with a hem stitching machine.

My principal object is to generally improve upon devices of this kind by providing one of comparative simplicity and durability wherein the details are such and so arranged as to permit employment of a comparatively small structure for accommodating a multiplicity of bobbins.

More particularly, I propose a rack of stepped formation wherein the horizontal shelf-like portions are provided with up-standing longitudinally spaced pins each of which is of a length and size to accommodate 20 a pair of conventional bobbins, whereby to permit a pair with the same color and shade of thread or silk to be arranged in a manner to facilitate selection and use.

Other objects and advantages will become 25 apparent from the following description and drawings.

In the accompanying drawings forming a part of this application, and in which like numerals are employed to designate like 30 parts throughout the same:—

Figure 1 is a front elevation of a bobbin rack constructed in accordance with the present invention,

Fig. 2 is a central vertical section through 35 the same,

Fig. 3 is a fragmentary detail view showing the approximate manner in which a pair of bobbins are racked.

Referring to the drawings in detail, it 40 will be seen that the entire device is made from sheet metal and is composed in the main of three separate sheets. One sheet comprises the base 1, the back 2, and the front 3. The sheet is bent upwardly as at 4 in forming the back wall, is bent upon itself as at 5 and downwardly as at 6 in forming the front. This front is of stepped configuration and includes horizontal shelves or rests 7 and vertical connections 50 8. The end of the sheet is bent upon itself upon its free end as indicated at 9 to form a reinforcing flange and it will be noted that this flange is disposed above the bottom and terminates inwardly of the same in order 55 to accommodate a sliding drawer 10 provided with a knob 11.

In order to close the opposite ends and to make for rigidity of structure, a pair of duplicate side plates 12 are employed. These side plates resemble bridge boards of 60 a stair structure in side elevation and they thereby accommodate the stepped formation of the front 3. The bobbin pins 13 may be in the form of rivets or the like, these being fastened to the horizontal shelves 7 at 65 equally spaced points in order to accommodate the bobbins 14. As previously stated, each pin will be of a length and size to accommodate a pair of bobbins. As is well known, the bobbins are ordinarily 70 used in pairs and each pair has the same color and shade of silk wound thereon.

Obviously, the convenience of maintaining the same in pairs for rapid use is quite evident. In connection with the stepped 75 front formation, and the correspondingly shaped edge of the side plates, it will be noted that the side plates are formed with tongues 15 and these are extended through slits in the vertical part 8 and then bent 80 over as shown to maintain the front assembled.

The connection between the other edges of the side plates and the back and bottom walls may be obtained in any appropriate 85 manner such as by soldering or any other form of connection. The outstanding advantage of a device of this kind is that it requires but very little space and may be placed directly upon the hem-stitching machine in a position convenient for use. In 90 this way, it will be directly in front of the user and will enable him to select the desired pair of bobbins in very little time and to remove them to be placed in position on 95 the machine. For instance, the device shown may be of substantially fourteen inches in height and considerably less in width for affording room for some one hundred and fifty-six bobbins, or seventy-eight different colors at the same time. In 100 this way the user can merely glance at the rack and pick out the desired colors in a few moments.

It is believed that by considering the description in connection with the drawings, persons familiar with inventions of this class will be able to obtain a clear understanding of the same. Therefore a more 105 lengthy description is thought unnecessary.

While the preferred embodiment of the invention has been shown and described, it

is to be understood that minor changes coming within the field of invention claimed may be resorted to if desired.

Having thus described my invention, what 5 I claim as new is:—

A bobbin holder of the class described comprising a sheet of metal bent upon itself to form a base, an upstanding rear wall and a downwardly and forwardly inclined 10 front, said front being bent at longitudinally spaced points to form a plurality of stepped formation, the lowermost horizontal portion terminating above and being spaced inwardly from the adjacent end of said

base, side plates connected with the front, 15 rear wall and base, the upper edges of said plates being notched to accommodate the steps of the front, said vertical portions of the steps being formed with openings and said side plates being provided with tongues 20 extending through said openings and bent upon themselves to hold the side plates in place, and a plurality of bobbin supporting pins carried by the horizontal portions of the steps. 25

In testimony whereof I affix my signature.

JAMES N. HARROD.
